ORONASAL MASK

Francis Eugene Randall, New Philadelphia, Ohio

Application October 23, 1944, Serial No. 560,069

1 Claim. (Cl. 128—142)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to oronasal masks adapted particularly for supplying oxygen or other gas to a person for the purpose of facilitating natural respiration and for producing artificial respiration. Such masks are commonly employed for supplying oxygen to aviators when flying at high altitudes and masks of this general type also have clinical use in hospitals for the treatment of patients by oxygen therapy, etc.

For the proper operation of oronasal masks of this type for supplying oxygen to a person for respiration, it is highly important that the mask fit the face properly so that a tight sealing engagement of the mask with the user's face is effected in order to eliminate the wastage of oxygen and leakage of air from the outside. One difficulty encountered with oronasal masks heretofore used is the lack of proper sealing engagement of the mask with the face of the wearer. One phase of this difficulty in connection with masks heretofore in use involves the fact that the face engaging portion of the mask tends to spread outwardly as the mask is pushed onto the face of the wearer so that it is necessary to rely largely upon the tension of the head straps to pull the marginal edges of the mask into sealing engagement with the wearer's face.

A primary object of the present invention, therefore, is to provide a construction of oronasal mask which tends to seal tightly to the face of the wearer as it is applied thereto.

A further object is to provide an oronasal mask wherein the marginal portion of the mask does not tend to spread outwardly as the mask is pushed onto the wearer's face.

Another object is to provide an oronasal mask having a face-engaging portion which tends to roll inwardly due to frictional engagement with the wearer's face as the mask is applied thereto.

Incidental to the foregoing objects it is a further object of the invention to provide an oronasal mask in which the construction of the marginal portion is such that when the mask is applied to the face of the wearer, the stress, due to such application, is applied to the wearer's face from the mask through the marginal portion thereof along lines passing through the wearer's head.

A further object is to provide an oronasal mask having a face engaging flap element extending from the marginal portion of the mask inwardly thereof and composed of elastic material that is

2

relatively more pliable than the body portion of the mask.

Another object is to provide an oronasal mask having a semirigid elastic body, the construction of the marginal portion of which is such that the stress, due to application of the mask to the wearer's face, is applied thereto through the marginal portion of the mask along lines passing through the wearer's head, in conjunction with a face engaging flap extending from the marginal portion of the mask and composed of elastic material that is relatively more pliable than the body portion of the mask, whereby said flap portion will tend to roll inwardly in engagement with the wearer's face as the mask is applied thereto.

A further object is to provide means for supporting the face engaging flap crosswise of the mask.

Another object is to provide an oronasal mask providing better sealing engagement in the region of the wearer's nose.

In carrying the invention into practice I provide an oronasal mask comprising a semirigid elastic body forming an open sided chamber adapted to receive the nose and mouth of the wearer, said body having an inwardly rounded marginal portion, the configuration of said marginal portion being such that, when the mask is applied to the face of the wearer with the nose and mouth of the latter disposed within said chamber, the stress, due to application of the mask to the wearer's face, is applied to the wearer's face from said body through the marginal portion thereof along lines leading from said marginal portion and passing through the wearer's head. Further, the configuration of said marginal portion is such that stresses, applied to the wearer's face from points on the marginal portion at opposite sides of the mask are applied to the wearer's face along convergent lines extending from said points and passing through the wearer's head.

I further provide a marginal face engaging flap portion composed of relatively more pliable elastic material than said body portion, said flap portion extending from the marginal portion of said body inwardly thereof. The body portion of the mask is preferably formed of rubber or like material having a sufficient rigidity or stiffness to retain its shape when pushed onto the wearer's face yet being sufficiently pliable to enable said body portion to yield slightly so as to conform to different facial contours. The flap portion of the mask is preferably composed of rubber or like material similar to that composing

the body portion but the flap portion is preferably of less thickness than the body portion so that the flap portion is relatively far more pliable and less shape-retaining than the body portion whereby the flap portion may have frictional engagement with the face of the wearer and may readily roll inwardly as the mask is pushed onto the face of the wearer and whereby the flap portion may more readily conform to minor variations in facial contour.

In accordance with the construction of the invention the body portion of the mask is made relatively thicker and stiffer at the marginal portion thereof, particularly in the region at which the face-engaging flap portion of the mask is joined thereto. The flap portion of the mask is preferably formed with a rolled marginal portion adjacent the region thereof at which the flap is joined to the body portion of the mask.

Other objects, advantages, and features of novelty will become apparent as the description of the invention proceeds in conjunction with the accompanying drawing, in which

Fig. 1 is a plan view of an oronasal mask embodying the invention looking toward the rear side thereof or the side which is positioned toward the face of the wearer when in use.

Fig. 2 is a longitudinal sectional view taken on the line 2—2 of Fig. 1.

Fig. 3 is a transverse sectional view taken on the line 3—3 of Fig. 1.

Fig. 4 is a transverse sectional view taken on the line 4—4 of Fig. 1.

Now referring to the drawing, the oxygen mask of the invention comprises a semirigid elastic or resilient shell or body 11 which may be molded out of rubber or other suitable material having the requisite characteristics of pliability as well as of firmness or semirigidity. The semirigid elastic body or shell 11 forms an open-sided chamber 10, the shape of which gives rise to the use of the term "shell" and this chamber 10 is adapted to receive the nose and mouth of a wearer when the mask is properly disposed on the wearer's face. The shell or body 11 is formed with an inwardly rolled or rounded marginal portion 11a, the configuration of which is such that, when the mask is applied to the face of the wearer so that the nose and mouth of the wearer are received within the chamber 10, the stress, produced at said marginal portion 11a when the mask is pressed onto the wearer's face, is applied to the wearer's face from said body 11 through the marginal portion 11a along lines indicated by the numerals 12 and 12a in Figures 3 and 4, leading from said marginal portion 11a and passing through the wearer's head.

The mask further comprises a face-engaging flap portion, generally indicated by numeral 13, and extending from the marginal portion 11a of the body 11 with the free edge 14 of the flap element 13 disposed inwardly of the chamber 10 formed by the body 11. The flap element 13 is composed of yieldable elastic resilient material similar to that of the body 11 but is relatively more pliable and less shape retaining than the body 11. The flap element 13 may, therefore, be composed of rubber or other suitable material having the requisite pliability so as to readily produce frictional engagement with the face of the wearer and readily conform with minor variations in facial contour. The flap element 13 comprises a relatively wide face-engaging portion 15 and is rolled or rounded as indicated at 16 to provide a somewhat angular flap portion 17 adjacent

the juncture of the flap 13 with the rounded marginal portion 11a of the body or shell 11.

The formation of the flap 13 with the angularly disposed portion 17 is designed to provide a certain degree of free movement of the flap 13 relative to the body or shell 11 so that the flap 13 is permitted to roll inwardly upon engagement of the face of the wearer with the relatively wide face-engaging portion 15 thereof as the mask is pushed onto the wearer's face in use.

It will be noted upon reference to Figs. 3 and 4 that the inwardly rolled marginal portion 11a is considerably thicker than the flap 13 extending therefrom to insure that the marginal portion 11a is stiffer and less pliable than the flap portion 13.

In practice the entire mask including the main shell or body 11 and the flap portion 13 may be molded integrally of the same material such as rubber or the like or the flap 13 may be made separate from the body 11 and said flap 13 subsequently joined to the rounded marginal portion 11a of the body 11 in any suitable manner. In any event, suitable provision will be made for making the entire shell or body 11 of sufficient stiffness to provide a certain degree of rigidity of the entire body 11 such that it will retain substantially the shape indicated in the drawings under the pressure of pushing the mask onto the face of the wearer and yet will be sufficiently pliable to enable the mask to conform to different facial contours. On the other hand, the flap element 13, while composed of similar elastic material to that of the body 11, is much more pliable or yieldable than the body 11 so that the flap element 13 is readily movable or flexible relative to the body 11 and so that the flap portion 13 may far more readily conform to minor variations in facial contour.

The flap element 13 is supported crosswise of the mask by means of an integrally formed web element 18. The flap element 13 is also formed with a bulged or depressed portion 19 at the area which is intended to bridge the nose of the wearer of the mask and depressed or bulged toward the interior wall 11b of the body 11.

The construction of the mask as above described is such that in use the mask is applied to the face of the wearer so that the face-engaging flap portion 15 of the flap 13 engages the wearer's face, indicated by lines 20 in Figs. 3 and 4, so that the wearer's nose and mouth are disposed within chamber 10 formed by the body 11. As the mask is pushed onto the wearer's face, the frictional contact of the face-engaging portion 15 of the flap 13 with the wearer's face tends to cause the flap portion 13 as a whole to roll inwardly so that even a portion of the angular part 17 of the flap may be engaged with the wearer's face, causing tight sealing engagement of the flap 13 with the wearer's face. This action is due in part to the stiffness of the mask shell or body 11 and the rounded contour of the marginal portion 11a, the configuration of which is such that the stress, due to application of the mask to the wearer's face, is applied to the wearer's face from the body 11 through the marginal portion 11a along lines leading therefrom and passing through the wearer's head.

It will also be noted that the stresses, due to application of the mask to the wearer's face, applied thereto from the body 11 through points on the marginal portion 11a at opposite sides of the mask, are applied to the wearer's face along con-

vergent lines 12 and 12a leading from said points and passing through the wearer's head.

The construction of the body 11 enables the mask to be pushed onto the face of the wearer without spreading of the rounded marginal portion 11a of the body 11 outwardly away from the face of the wearer.

The inwardly rolling action of the flap element 13 as the mask is pushed onto the face of the wearer assists in the adjustment of the mask to different facial contours with resultant tight sealing facial engagement so that a given size of mask is adaptable to a wider range of facial sizes and contours than would otherwise be the case. The relative stiffness or semi-rigidity of the mask shell or body 11 is of itself largely sufficient to prevent lateral spreading of the inwardly rolled marginal portion 11a as the mask is pushed onto the face of the wearer but the cross web 18 further assists this result. Primarily, however, the function of the cross web 18 is to maintain the relatively yieldable flap element 13 in proper position so that the face-engaging portion 15 thereof will properly frictionally engage the face of the wearer.

It will be understood that the mask has an intake conduit 21 leading to the interior of the chamber 10 through the body 11, said body having in its front wall a pocket 22 which has an exhaust passage 23 descending therefrom. The 30 intake passage and the exhaust pocket and passage will be provided with suitable valves (not shown).

Having thus described my invention, what I claim as new and desire to secure by Letters 35 Patent is:

An oronasal mask comprising a semirigid elastic body forming an open sided chamber adapted to receive the nose and mouth of the wearer, said body having an inwardly rounded and inwardly 40

convergent marginal portion, the configuration and rigidity of said marginal portion being such that, when the mask is applied to the face of the wearer, with the nose and mouth of the latter disposed within said chamber, the stress, due to application of the mask to the wearer's face, is applied to the wearer's face from said body through said marginal portion thereof along converging lines leading from said marginal portion and passing through the wearer's head, a face-engaging flap element extending from the marginal portion of said body with the free edge of said flap element positioned within said chamber and including an upper inwardly bulged portion adapted to fit over and span the bridge of the nose of the wearer, said flap element being composed of elastic material and relatively more pliable than said body portion, and a web portion formed integral with said flap element and extending substantially straight across the mask between the opposite portions of the free edge of said face-engaging flap element and being attached at its ends only to said flap element.
